CLAIM

The ornamental design for a transparent card with opaque portion, as shown and described.

DESCRIPTION

FIG. 1 is a front view of a first embodiment of a transparent card with opaque portion showing the design;

FIG. 2 is a rear view thereof.

FIG. 3 is a front view of a second embodiment of a transparent card with opaque portion showing the design; and,

FIG. 4 is a rear view thereof.

The broken line showing of numbers and a horizontal strip are included for the purpose of illustrating portions of the article and form no part of the claimed design.
